REFRIGERATION WITH SOLID CARBON DIOXIDE

Frank Heywood, Norton-on-Tees, England, assignor to Imperial Chemical Industries Limited, a corporation of Great Britain

Application January 25, 1933, Serial No. 653,534,
and in Great Britain January 29, 1932

4 Claims. (Cl. 62—91.5)

When employing blocks of solid carbon dioxide evaporating into air for refrigerating two problems are commonly met with. Firstly, it may be difficult to secure a sufficiently rapid rate of evaporation of the block to provide the desired cooling effect, as for instance in the case of refrigerated spaces of large size the walls of which are relatively poor heat insulators. Secondly it is difficult to secure a uniform rate of evaporation during the life of the block since this rate is a function of the superficial area of the block, which decreases as increasing quantities of carbon dioxide are evaporated away.

These difficulties may be overcome by using, instead of a single large block, a number of comparatively small blocks, or a block having a large surface to volume ratio, e. g. thin flat plates, but a considerable loss due to evaporation must occur in sub-dividing large blocks into such plates, while the handling of a large number of small pieces is a drawback.

According to the present invention, in a process of refrigerating with solid carbon dioxide evaporating into a current of air, a rapid and relatively uniform rate of evaporation is obtained by supporting the block on a number of horizontal heat-conducting bars, the edges of which in contact with the block are preferably sharp, so that as a result of the weight of the block and the evaporation at the surfaces of the heat-conducting bars the block is slowly divided into a number of separate slabs which depend between the bars. Means are preferably provided to cause the down draught of air which passes over the surface of the carbon dioxide to pass between the vertical slabs which are thus formed. In this manner the block is divided into a number of sections of relatively large superficial area without the loss of any refrigerating value outside of the system and since the further evaporation takes place chiefly at the sides of the slab thus formed, a substantially constant rate of evaporation is maintained.

In the accompanying drawing I have shown, more or less diagrammatically, my invention embodied in a refrigerating or cooling unit of a type adapted to be used in treating air, air being circulated through the unit. In the drawing,

Fig. 1 is a view in sectional elevation of a unit embodying my invention, and

Fig. 2 is a view in sectional elevation taken along line 2—2 at right angles to Fig. 1.

As illustrated in the showing, element 1 is a heat insulated chamber provided with an adjustable damper 2 at the top. This damper may

be slid laterally so as to establish communication of the chamber with the atmosphere to a greater or less degree, thereby adjusting the flow of air into and through the chamber. Within the chamber is mounted grid 3 composed of a plurality of massive cutting bars made of aluminum or other good heat conductive metal; these bars having sharp edged tops. The chamber has a liner 4 shown as of heavy metal, forming a large radiating surface. Within the chamber, horizontal plate 5 is also shown as of heavy metal and having a thick edge, extending around three sides of the chamber and in good thermal contact with the liner. It is advantageous to make the liner, plate and the grid bars integral by welding or otherwise, thereby facilitating passage of heat. The plate has an opening adapted to receive a block or brick of solid carbon dioxide.

Liner, plate and grid form a practically unitary structure, thermally speaking. With aluminum as the structural material, because of its high heat conductivity, local temperature differences are minimized. The plate is spaced away from one side of the chamber leaving a free passage therebetween for circulating gases. Below the grid is a tray 8 which serves the double purpose of guiding circulating gases and of collecting any liquid or frozen water which may form on the surface of the solid carbon dioxide and pass downward. A cock 9 is provided in the base of the tray to draw off water from time to time.

In using the apparatus, a block of carbon dioxide 6 is placed upon the grid. The drawing shows the apparatus after a block has been in position for some time, and partially consumed by evaporation. Warm air entering the chamber at the top imparts heat to the liner, and heat is thence transferred by means of plate 5 and the grid, to the block of dioxide. Because of the good interchange of heat between the massive grid, plate and liner, the grid bars are kept warm and they cut their way, so to speak, through the block. Evaporation is rapid at the surfaces of the solid carbon dioxide block adjacent the grid; more rapid than from the surfaces exposed directly to the air. As the bars cut through the block, in the course of time it assumes the appearance shown with slabs 7 of solid dioxide hanging or depending below the grid between the bars.

Air enters the chamber through the top damper 2, passes between the block of solid carbon dioxide and the liner, below the grid, between the depending slabs of carbon dioxide, over the

tray, and out the bottom. This flow is indicated by arrows in Fig. 2. Inspection of the figure shows that the total area of cooling surface, including the area of the block, the area of the liner, and the area of the several slabs, is large. Accordingly, a relatively small apparatus element suffices to cool a considerable volume of air passing through it. The carbon dioxide is renewed from time to time.

10 The chamber being heat insulated, as shown, a wide range of evaporation rates can be obtained by varying the opening of the damper 2.

15 A refrigerating unit as described above was constructed with a grid consisting of eight parallel aluminum bars, 10.25 inches in length, 1 inch in depth and 0.25 inches in thickness. The bars were sharp edged at the top, the top edges meeting at an angle of 60 degrees, and were spaced 1 inch apart. A block of solid carbon 20 dioxide weighing originally 45 pounds was placed on the grid and observations were made of the weight of the block after regular periods of time. The results are given in the following table and indicate the approximately uniform rate of 25 evaporation of the block.

	Time in hours	Weight of block
